UNITED STATES PATENT OFFICE.

DAVID C. OWENS, OF CLIO, ALABAMA.

LEVEL.

1,207,202.

Specification of Letters Patent.

Patented Dec. 5, 1916.

Application filed December 31, 1915. Serial No. 69,635.

To all whom it may concern:

Be it known that I, DAVID C. OWENS, a citizen of the United States, residing at Clio, in the county of Barbour and State of Alabama, have invented certain new and useful Improvements in Levels; and I do hereby declare the following to be a full, clear, and exact description of the invention, such as will enable others skilled in the art to which it appertains to make and use the same.

This invention relates to levels, and more particularly to a level which includes a weighted pendulum structure, and the primary object of the invention is to provide a level, which is simple in construction, substantial, one which will remain accurate without adjustment through all atmospherical conditions, and which is constructed so as to eliminate delicate parts which are apt to become inoperative upon rough handling.

A further object of this invention is to provide a level structure as specified, wherein the pendulum or bob is pivotally supported by transparent semi-housings, which form substantially, jewel bearings for the pivot arms of the pendulum or bob, and to provide a compact structure for detachably holding the transparent semi-housings in their proper positions with respect to the body of the level.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like and corresponding parts throughout the several views, and in which:

Figure 1 is a side elevation of the level. Fig. 2 is a section on the line 2-2 of Fig. 1. Fig. 3 is a detail view of the pendulum or bob. Fig. 4 is a detail view of one of the transparent semi-housings, and Fig. 5 is a detail view of the base plate. Fig. 6 is a horizontal section on the line 6-6 of Fig. 1.

Referring more particularly to the drawings, 1 designates the body of the level as an entirety, which may be constructed of metal, wood, or any other material suitable for the purpose or commonly employed in the construction of level. In the drawings, 55 a metallic body is shown which is formed of plates 2 and 3, which are connected in

any suitable manner to form the ordinary I-shaped body of metal levels. The plates 2 and 3 are provided with openings 4 positioned centrally therein, and with annular recesses 5 which surround and communicate with the openings 4. The recesses 5 are formed in the inner abutting faces of the plates or sections 2 and 3. The pendulum or bob inclosing housing, includes, a pair of transparent semi-housings 6 and 7, which are preferably constructed of glass and have annular flat portions 8 extending around their marginal edges. The semi-housings 6 and 7 bulge outwardly so as to provide a space as indicated at 9 to permit of the free and unimpeded pivotal movement of the pendulum or bob 10.

Metallic facing rings 11 and 12 are provided which extend over the periphery of the annular rings 8 and also over the outer surfaces of the rings. The inner surfaces of the rings 8 abut, and the semi-housings 6 and 7 are held connected to each other by pins 13 which extend through openings 14 formed in the rings 8. The facing rings 11 and 12 have outwardly extending ears 14 formed thereon the inner surfaces of which ears abut. The ears 14 are connected, and held in engagement with each other by suitable fastening means, such as screws as indicated at 16. The ears 14 are seated in the recesses 5, formed in the abutting faces of the plates or sections 2 and 3. The facing ring 11 has graduations as indicated at 18 formed thereupon, which graduations are positioned at angles of 90 degrees with respect to each other about the circumference of the ring 11.

The pendulum or bob 10 comprises a body 20 which has a pointer 21 formed upon and extending upwardly from the center of its upper surface. Pivot pins 22 and 23 are formed integrally with the body 20 and project transversely to the pin or finger 21. The ends of the pivot pins 22 and 23 are rounded, and rest in recesses 24 which are formed centrally within the inner surfaces of the center of the semi-housings 6 and 7. The recesses 24 have circular walls so as to provide efficient bearings for the rounded ends of the pivot pins 22 and 23 for permitting of a free and unimpeded swinging of pivotal movement of the pendulum or bob. The sides of the body 20 of the pendulum or bob terminates in an indicating point as shown at 25, which is adapted for

coaction with the indicating point or finger 21 and a diametrically opposed pair of the 21 graduations 18 in the employment of the level.

5 If it is so desired, the level may be used in a vertical manner, as a plumb without departing from the spirit of this invention.

10 In reducing the invention to practice, certain minor features of construction, combination and arrangement of parts may necessitate alterations to which the patentee 10 is entitled, provided such alterations are comprehended within the scope of what is claimed.

15 What is claimed is:—

In a pendulum structure, the combination with a body, of a pendulum including a body, an indicating finger formed integrally with said body and projecting outwardly from 20 the center of the upper surface of the body, a pair of pivot pins formed integrally with the upper surface of said body and projecting transversely therefrom with respect to said

indicating finger, the sides of said body merging into each other and forming an indicating point formed upon the lower end 25 of said body, said indicating point being positioned in alinement with the point of said indicating finger, a pair of semi-housings carried by said body and being constructed of transparent material, said semi-housings provided with recesses formed in their inner faces at the center thereof, said recesses forming bearings for the ends of 30 said pivot pin for pivotally supporting said pendulum, annular rings formed about the edges of said semi-housings, and metallic facing rings encompassing said rings and being connected for connecting said semi-housings.

In testimony whereof I affix my signature in presence of two witnesses.

DAVID C. OWENS.
